FIG. 1.

FIG. 2.

Inventor:
Franz Lawaczeck

by *Lawaczeck*
Atty.

UNITED STATES PATENT OFFICE

FRANZ LAWACZECK, OF MUNICH, GERMANY

SIPHON SPILLWAY

Application filed June 20, 1927, Serial No. 200,185, and in Germany June 21, 1926.

My invention refers to the art of hydraulic engineering and provides means for utilizing to the utmost extent the head and water power of flowing waters, for instance rivers, 5 at mean and low water, while avoiding the danger from high water.

In the utilization of the head and hydraulic power of rivers one is constantly confronted with the problem, how to deal with 10 the water in rivers provided with weirs or retaining dams in such manner that the head at mean and low water will correspond approximately to the usual head at high water without allowing the head at high water to 15 get so high as to allow the water to overflow the banks below the weir.

The present invention in dealing with this problem makes use of the well known siphons 20 extending across the top of the weirs for conveying across the weir the surplus water to be disposed of during the periods of high water.

As is well known high water in consequence of the greater velocity of flow of the 25 water in the river consumes far more head by friction and eddying per unit of cross-sectional area than the comparatively small quantity of mean and low water. Therefore hitherto the overflow edge of the retaining 30 dams had to be disposed at a considerably lower level than would be admissible for low and mean water in order to prevent the water from overflowing the banks in front of the weir in spite of the materially higher banking curve extending upstream. The loss of 35 head hereby occasioned at low and mean water is very considerable, more especially in rivers carrying great quantities of high water and will sometimes amount to more 40 than the head which is available for utilization.

These drawbacks are avoided according to 45 the present invention by automatically keeping the head higher at normal and low water than at high water, the head and drop at high water being determined by the upper admission edge of the well known siphons extending across the dam, which is arranged at a correspondingly lower level, the siphon 50 being set operating, whenever the upstream

level predetermined for mean and low water is overstepped, by quickly and automatically exhausting air from the siphon. In consequence of this arrangement the edge of the 55 weir no more determines the head and the starting of the siphon and the great advantage is obtained that the top edge of the weir need not extend exactly in a horizontal line. In spite thereof the adjusting of the water level is effected in a more sensitive manner 60 than in those cases where the water level is made dependent from the height of the weir edge. A further important advantage results from the damming up of low and mean 65 water to the high water level, because now the cross-sectional area of the river bed at high water, which is utilized only during the short period of high water, now constitutes a powerful accumulator for normal operation 70 so that at least one daily make up for the surplus output of the power station can now be accumulated in the space of the river bed, 75 which was hitherto not utilized.

In the drawings affixed to this specification and forming part thereof a retaining dam embodying my invention is illustrated diagrammatically by way of example.

In the drawings,

Fig. 1 is a section of the dam with the siphon extending across it and with automatic means for setting same operating.

Fig. 2 is a diagram showing an improved construction of the device for actuating the siphon.

Referring first to Fig. 1, *d* is the dam, *e* is its top and *f* is the siphon extending across the top *e* in such manner that its upper admission edge *g* is situated below the upper water level, its upper exhaust edge *h* below 80 the low water level. Exactly at upper water level, so as to determine the same, is disposed the top edge *i* of the admission member *l*, preferably of funnel shape, of the hydraulic engine *m*, which drives an air pump, the suction pipe *k* of which sucks air from the summit of the siphon bend and thereby sets the siphon operating. The air compressed by the engine *m* can for instance be conducted together with the exhaust water from the 125

engine *m* to the low water level by means of the canal *n* formed in the dam *d*.

The siphons *f* can always be sufficiently efficient to suck off more water than will flow in at times of high water. By quickly and automatically exhausting the air from the siphon *f* by means of the tube *k* and engine *m*, a quick starting of the siphon is provided for at the moment, when the upper water level predetermined for mean and low water is overstepped. Whenever high water is imminent, the siphons *f* will act towards lowering the upper water level down to that level which is determined by the admission edges *g*. Thus two different upper water levels are created according to whether the siphon is operating or not. In the latter case, that is during low and mean water, the upper water level is kept by the admission edge *i* of the funnel at a predetermined level which in all cases is higher than the level now used. On the other hand, if during high water the siphon *f* is in operation, the upper water level will be lowered down to the admission edge *g* of the siphon which is arranged below the edge *i* of the funnel. The difference of level between the edge *g* and the highest water level at low water is such that the lowering of the upper water level brought about by means of the siphon *f* suffices to carry the high water toward the weir without any undue head.

I prefer making the admission funnel *i* adjustable either before or during operation in order to be able to regulate the upper water level. This is illustrated in Fig. 2 together with very sensitive means for setting the siphon *f* operating. Here the upper funnel-shaped part *i*₁ of the tube *i*₂ leading to the engine *m* is movable and is adjusted by a float *q* or the like and lever *r* which is supported on the arm *p* of tube *i*₂. If the upper water level exceeds a predetermined level, the admission funnel *i*₁ is lowered quickly and thereby causes the exhausting engine *m* and the siphon *f* to be quickly started operating. Although afterwards the air pump is stopped by lowering the float *q* and raising the funnel *i*₁, the siphon *f* will nevertheless continue its operation until the high water wave has disappeared altogether and the upper water level has sunk below the admission edge *g* of the siphon. Only after this has taken place, the air entering the siphon *f* will stop its operation.

The new dam above described, while forming a very sensitive means of adjusting the upper water level, also affords a possibility of producing a higher head with quantities of water which are less than the quantities to be disposed of at high water. I thereby obtain a gain of efficiency of the water power plant as a whole and also a greater depth of the river for the purposes of navigation. The top of the weir which can be disposed at any

desired height above the highest normal water level, need not extend exactly in the horizontal.

I wish it to be understood that I do not desire to be limited to the exact details of construction shown and described for obvious modifications will occur to a person skilled in the art.

I claim:—

1. A siphon spillway comprising a siphon and automatic starting means therefor, an adjustable admission member for the water to actuate said starting means being arranged at the highest admissible upstream level.

2. A siphon spillway comprising a siphon and automatic starting means therefor, an adjustable admission member for the water to actuate said starting means being arranged at the upstream level and a float for adjusting said member.

In testimony whereof I affix my signature.

FRANZ LAWACZECK.
